UNITED STATES PATENT OFFICE.

CARL G. LINDSTRAND, OF BISBEE, ARIZONA TERRITORY.

MACHINE FOR SLAG-BREAKING.

No. 874,692.

Specification of Letters Patent.

Patented Dec. 24, 1907.

Application filed July 29, 1907. Serial No. 386,126.

To all whom it may concern:

Be it known that I, CARL G. LINDSTRAND, citizen of the United States, residing at Bisbee, in the county of Cochise and Territory of 5 Arizona, have invented certain new and useful Improvements in Machines for Slag-Breaking, of which the following is a specification.

This invention has for its object a simple and efficient construction of machine for 10 slag breaking in the operation of rolling strip or sheet iron, which will produce a clean surface on the sheet or strip as it passes between the rolls, which will do away with the ordinary revolving brushes, a blast pipe being 15 substituted therefor so as to blow off the slag after it is broken, and which will be so arranged that the iron, after passing through the slag breaking device will pass directly to the rollers, no time being lost in cleaning it 20 and allowing it no chance to cool before being rolled.

With these and other objects in view as will more fully appear as the description proceeds, the invention consists in certain constructions, combinations and arrangements 25 of the parts hereinafter described and particularly pointed out in the appended claims.

For a full understanding of the invention and the merits thereof and also to acquire a 30 knowledge of the details of construction and the means for effecting the result, reference is to be had to the following description and accompanying drawings, in which:

Figure 1 is a sectional side elevation illustrating my improvements; Fig. 2 is a top plan view thereof, the upper roll and blast pipe being omitted; Fig. 3 is a detail view, partly broken away of the blast pipe; and, 35 Fig. 4 is a detail perspective view of a portion of the pivoted frame.

Corresponding and like parts are referred to in the following description and indicated in all the views of the drawings by the same reference characters.

Referring to the drawings, the numerals 1 and 2 designate respectively the upper and lower rolls of a mill, and 3 designates the guide casing of my improved slag breaking device, said casing being mounted in any desired manner on any stationary portion of the mill frame work immediately in front of the rollers, being preferably provided with a tapered end, as shown, so as to fit to some extent between the rollers. The guide casing 55 4 is provided with a passage 4 extending

therethrough and through which the sheet or strip iron 5 is fed to the rollers.

A frame is pivoted to the casing 3 at the entrance end of the same, said frame consisting of a transversely extending rod 6 and two angularly disposed arms 7 and 8 connected to the ends of the said rod, the extremities of the arms being secured to the casing 3 by the pivot studs or screws 9. The arm 8 is provided with a lever extension 8^a to which the handle 10 is attached, as clearly illustrated in the drawings. The rod 6 is positioned between two beams 11 and 12, the outermost beam being preferably movable in its supports or bearings, so as to 70 make a short break for fine iron and a longer break for coarse iron. Preferably the lever extension 8^a has a screw 13 working therein and adapted to impinge against the beam 12 at one side of the sheet or strip 5, so as 75 to limit the movement of the rod 6 as it is pressed against the iron.

A blast nozzle 14 is supported in any desired way above the casing 3, the lower end of said nozzle or blast pipe being flattened and pointing downwardly and at a slight angle to the upper surface of the sheet or strip of iron just as the same passes into the casing 3 on its way to the rollers 1 and 2. 85

In the practical operation of my improved slag breaking device, the lever comprised by the parts 8^a and 10 is first raised to elevate the rod 6 so as to let the iron into the rollers. The rod 6 is then pressed down 90 upon the strip or sheet, the latter being bent, as clearly illustrated in the longitudinal sectional view, downwardly between the two beams 11 and 12. As the slag is thus broken by the rod 6 and beams 11 and 12, 95 the slag will be removed from the upper surface of the sheet or strip by means of the blast pipe or nozzle 14 and the iron with a clean surface will pass directly through the casing 3 between the rollers without having 100 a chance to cool off. Preferably the rear beam 12 is somewhat higher than the front beam. Both beams and the rod 6 are preferably made of steel.

Having thus described the invention, 105 what is claimed as new is:

1. The herein-described slag breaking apparatus, comprising a casing adapted to be supported in front of the rollers of a mill, a frame pivotally mounted on said casing and 110

embodying a transversely extending rod, a pair of spaced beams mounted in front of said casing on opposite sides of said rod, a lever secured to said frame and adapted to move the rod downwardly between the beams, and a blast nozzle mounted above the casing adapted to direct a blast of air towards the beams.

2. A slag breaking apparatus comprising
10 a casing adapted to be mounted in front of the rollers of a mill, transversely extending spaced beams supported in front of said cas-

ing, and a frame pivotally mounted on said casing at the front thereof and consisting of a transversely extending rod adapted to move between the beams, and two side arms connected to said rod, one of said side arms being formed with a lever extension.

In testimony whereof I affix my signature in presence of two witnesses.

CARL G. LINDSTRAND.
